US00D605497S

(12) **United States Design Patent**
Lulla et al.

(10) **Patent No.:** **US D605,497 S**
(45) **Date of Patent:** **** *Dec. 8, 2009**

(54) **CANTILEVER**

(75) Inventors: **Amar Lulla**, Mumbai (IN); **Xerxes Rao**, Mumbai (IN)

(73) Assignee: **Cipla Limited**, Maharashtra (IN)

(**) Term: **14 Years**

(21) Appl. No.: **29/302,212**

(22) Filed: **Jan. 11, 2008**

(30) **Foreign Application Priority Data**

Jul. 13, 2007 (ID) 211209

(51) **LOC (9) Cl.** **08-05**

(52) **U.S. Cl.** **D8/354**

(58) **Field of Classification Search** D8/343,

D8/349, 354, 363, 373, 380, 381; D25/61; D26/145; 108/108; 211/96, 187, 193; 248/200,

248/205.3, 242, 243, 245, 250, 629; D6/574

See application file for complete search history.
